UNITED STATES PATENT OFFICE.

HEINRICH LEMCKE, OF HILDEN, GERMANY.

APPARATUS FOR CASTING HOLLOW INGOTS.

Application filed January 21, 1927, Serial No. 162,559, and in Germany August 2, 1926.

My invention refers to the art of rolling tubes from malleable cast-iron and more especially to the blanks, from which such tubes are rolled. It is an object of my invention to provide a new kind of blank and also the means for producing same, whereby rolled tubes of this kind can be produced in a cheaper and more efficient manner than was hitherto possible.

10 In endeavouring to avoid the costly and difficult punching of solid blocks of malleable iron, when producing blanks to be rolled out into tubes, it has been suggested to produce such blanks by casting, the cast-iron obtained from the Bessemer converter, the Siemens-Martin furnace or the electrical furnace being re-melted and hollow ingots being obtained by casting this re-molten metal. It has further been suggested to produce such blanks by centrifugal casting.

15 According to the present invention I avoid the re-melting by directly casting the malleable iron obtained in the Bessemer converter, the Siemens-Martin furnace, the electrical furnace and the like from raw iron into the shape of hollow blanks adapted to be rolled out into tubes, making use of suitable cores which can be utilized in a greater number of succeeding operations.

20 In thus casting the blanks direct from the melting oven, I obtain hollow substantially cylindrical ingots, consisting of raw malleable cast-iron, which can be rolled out directly into tubes.

25 In carrying out this process, I prefer using a plurality of juxtaposed casting moulds, a core extending axially into each mould, and I provide means for simultaneously filling all the moulds and for simultaneously withdrawing the cores from all the moulds, when the cast metal has solidified in the moulds.

30 In the drawings affixed to this specification and forming part thereof two modifications of a device embodying my invention are illustrated diagrammatically by way of example.

35 In the drawings,

Fig. 1 is an elevation, partly in vertical section, and

Fig. 2 is a plan view of a first modification, while

Fig. 3 is a view, similar to Fig. 1, of a second modification.

40 Referring first to Figs. 1 and 2, 1, 1 are

eight cylindrical moulds mounted in two groups of four on a common supporting structure 2. 3, 3 are conical hollow cores made of iron or some other suitable material, which extend axially through said moulds and through openings provided in the supporting structure 2. A centrally disposed hopper 7 serves for filling the moulds with cast metal by way of suitable conduits 8 formed by hollow bricks 19, the filling of the moulds being effected from below as shown in dotted lines in Fig. 1. As soon as the cast metal has solidified and cooled down sufficiently in the moulds, water under pressure is introduced through the openings 9 into the cylinders 6, whereby the plungers 5 and plunger rods 5' are forced downwards, carrying with them the bridge piece 4 and the cores 3 connected to it by nuts 10. In order to facilitate the withdrawal of the cores from the castings, the cores have a conical form. As shown in Fig. 1 I prefer providing the cores with means for cooling them, the cores being made hollow and a water pipe extending into each core. The cooling water introduced through this pipe can escape through an opening in the cap 13 forming the bottom closure of the core.

45 Preferably the water is introduced only after the cast metal has cooled down sufficiently to allow the core to be removed. The heat of the fluid material having caused the core to expand, the cooling action of the water will cause a contraction of the core whereby it can be withdrawn from the casting with comparative ease.

The moulds 1 are then lifted off the casting by suitable mechanical means and the hollow blanks 11 are now ready to be removed to the rolling mill.

50 While in the modification shown in Fig. 1 the cores are shown as being introduced into the moulds from below, Fig. 3 shows a modification in which the cores are introduced into the moulds from above. Here the cores 3' are suspended from a top bridge piece 14 carried by plungers 15 surrounded by hydraulic cylinders 16, into which water under pressure can be forced by way of the

bottom opening 17. In order to prevent the moulds 1' from being lifted also, they must be firmly connected with the supporting structure 18. In this modification as well as in the one shown in Fig. 1 hollow cores may be provided with means for water cooling them. The molten metal is introduced into the moulds from below, as shown more particularly in Fig. 1.

10 Instead of lifting the moulds off the castings, as described with reference to Fig. 1, means can also be provided for tipping the moulds together with the castings, which can then easily be withdrawn from the moulds by hand.

The hydraulic lifting means here shown can also be replaced by mechanically or electrically operated means.

In order to facilitate the withdrawal of 20 the cores, an insulating coating may be arranged on the surface of the cores, such coating consisting for instance of graphite, clay, a mixture of graphite, oil and sand or the like and being renewed after each casting 25 operation.

If solid cores are employed, I prefer making them of cast-iron, while the hollow cores are made of steel.

The withdrawal of the cores can further 30 be facilitated by using cores in two parts divided along their axes.

The hollow bricks 19 as well as the casting hopper 7, which also consists of such bricks, must be replaced by fresh ones after 35 each casting. The bricks are broken to

pieces and the cast material contained therein is used as scrap.

I wish it to be understood that I do not desire to be limited to the exact details of construction shown and described, for obvious modifications will occur to a person skilled in the art.

I claim:—

1. Device for casting hollow ingots comprising a supporting structure, a plurality of casting moulds mounted on said structure, a core extending axially into each mould and spaced from its inner walls, a bridge piece extending substantially in parallel to said structure and having all said cores fixed to it, a pair of hydraulic plungers fixed to said bridge piece, one at each end, and a hydraulic cylinder at each end of said structure enclosing each plunger.

2. Device for casting hollow ingots comprising a supporting structure, a plurality of casting moulds mounted on said structure, a core extending axially into each mould and spaced from its inner walls, a bridge piece extending substantially in parallel to said structure and having all said cores fixed to it, a pair of hydraulic plungers fixed to said bridge piece, one at each end, a hydraulic cylinder at each end of said structure enclosing each plunger and common means for simultaneously pouring metal in all said moulds.

In testimony whereof I affix my signature.

HEINRICH LEMCKE.
